E. KÄGI.
COMBUSTION ENGINE GOVERNOR.
APPLICATION FILED SEPT. 21, 1914.

Patented Feb. 2, 1915.

UNITED STATES PATENT OFFICE.

EMIL KÄGI, OF WINTERTHUR, SWITZERLAND, ASSIGNOR TO BUSCH-SULZER BROS.
DIESEL ENGINE COMPANY, OF ST. LOUIS, MISSOURI, A CORPORATION OF MISSOURI.

COMBUSTION-ENGINE GOVERNOR.

1,127,012.

Specification of Letters Patent. Patented Feb. 2, 1915.

Application filed September 21, 1914. Serial No. 862,711.

To all whom it may concern:

Be it known that I, EMIL KÄGI, a citizen of the Republic of Switzerland, resident of Winterthur, Canton of Zurich, Switzerland, 5 have invented the following-described Improvements in Combustion-Engine Governors.

The invention consists in the combination of parts and mode of operation and adjustment of centrifugal governors intended for the control of the fuel supply, or other speed controlling organ, of internal combustion engines, more especially combustion engines used for propelling vehicles through electric-generator-motor transmission.

It is desirable to operate combustion engines at more than one normal speed, retaining governor control of the engine speed at all speeds. For instance, in the vehicle 20 having electric transmission, it is often desirable to run the engine at a fixed higher speed during the propulsion of the vehicle and at a fixed lower speed when the wheel-driving electric motors are at rest, and in 25 both cases it is desirable that the governor shall exert the same character of control upon the engine, that is to say, shall respond equally to equal fluctuations. My invention provides simple and effective means 30 for the purpose, and which are particularly adapted to accommodate or compensate the different conditions of vibrations and motions of the vehicle when the latter is in motion and at rest.

35 In the drawing forming part hereof, Figure 1 is a central longitudinal section of a governor, with parts in elevation, including the governor lever of the engine, the engine itself being omitted as unnecessary to an 40 understanding of the invention; Fig. 2 shows sectional details of the control rod in two positions, as later described; Fig. 3 is a perspective view of the governor; and Fig. 4 is a bottom plan, showing the governor 45 spindle and control rod in cross-section.

The governor lever 1 may be assumed to be organized with the engine proper, not shown, in any suitable way, for instance, so as to control the suction valve of the fuel 50 pump of Diesel type engines, or any other

analogous part of other engines, to regulate the speed at which the engine runs. The hollow spindle 2 may be assumed to be geared to the engine crank-shaft so as to be rotated thereby. This governor spindle 55 carries fast upon it a spider bracket 3, on which are pivoted two pairs of opposite fly-ball-levers. These are marked 4 and 4^a, respectively, and each lever of each pair is a bell-crank lever with its longer arm normally upstanding and carrying the fly-ball, and its shorter arm projected radially toward the axis of the spindle. The fulcra of the several levers, marked 5, are indicated as equipped with ball bearings, of conventional type, and the ends of the several short arms are provided with ball-bearing rollers, marked 6 and 6^a, respectively. These rollers are adapted to thrust upwardly upon the bottom side of a spring-loaded thrust 70 collar 7, which forms the lower part or end of a dash pot cylinder 8, which latter is fitted to slide on the governor spindle 2, and is intended to be filled with oil or other mobile medium. The dash-pot piston 9 is 75 fixed to the spindle so that movement of the collar 7 and cylinder 8 in either direction on the spindle is retarded or damped by the resistance opposed to the passage of the liquid through or past the piston. 80 Above the range of motion of the dash-pot cylinder, the spindle 2 also carries, screwed thereon, an abutment 10 for the governor spring 11, the other end of which abuts against the collar 7, opposing upward movement of the latter, as produced by the fly-ball levers, and tending to hold them upright.

The governor spindle 2 is hollow, as above mentioned, and at about the level of the 90 lever fulcra is transversely slotted as indicated. A short rod 12, swiveled to the ring 13 of the governor lever 1 extends through the interior of the upper part of the spindle to the slotted portion, where it is cross-pinned to the neck of the dash-pot cylinder, between the latter and the abutment collar 7. Movement of the dash-pot cylinder resulting from its engagement by the fly-ball levers is thus transmitted to the governor 95 100

lever, and the engine is accordingly controlled by the position of the balls, which latter is in turn determined by the speed of the engine, as will be understood.

5 For the higher normal speed in the present case only the two fly-ball-levers 4 are allowed to exert their efforts upon the thrust-collar 7, the other pair 4^a being held out of engagement therewith by means of a 10 rod 14 disposed within the lower part of the hollow governor spindle. This rod is slotted at its upper end, where the spindle is also slotted, and receives the two ends, 14^b, of the short arms of levers 4^a, in such 15 manner that when the rod 14 is pulled downwardly within the spindle it will pull the thrust-rollers 6 away from the thrust-collar 7, or at least hold them from acting thereon. The centrifugal action on these 20 levers is thus held ineffective upon the engine. The right hand part of Fig. 2 illustrates this position of the rod and the parts it controls. For the lower normal speed the control rod 14 is released or pushed up- 25 wardly to allow the said levers to act on the collar, so that all four balls will then swing outwardly by the centrifugal effect, producing an increased action on the governor lever or member 1. The left hand part 30 of Fig. 2 illustrates this position of the rod. By thus changing the number of fly-ball levers allowed to act on the engine, the latter can be set to maintain either one of two normal, governor-controlled, speeds, and by 35 the provision of extra levers controlled in like manner and successively or progressively, more than two, in fact any desired number of normal speeds can be established while the engine is running and the governor 40 not rotating. In each case the governor will have the same characteristics as to speed variation. The elements may be proportioned to this end; that is to say, with only the main centrifugal elements, the 45 balls 4, in operation, the engine speed may be, say, 200 R. P. M. normal, with a speed variation of plus or minus 3%; the normal speed with one set of supplementary centrifugal elements in operation may be then 50 R. P. M., and will have a similar speed variation of plus and minus 3%, while a second set of centrifugal elements might be brought into operation reducing the normal speed to 50 R. P. M., still with a speed 55 variation of plus and minus 3%. By speed variation is meant the difference between the speed maintained at the extreme points of movement of the centrifugal elements as compared to the normal speed when these 60 elements are in their mean position.

The heavy spring 11 and the powerful dash-pot above described are so related to the centrifugal elements, as retarding and loading factors that, in the case of the en-

gine-driven vehicle, the desired speed variation will be maintained when the vehicle is in motion and also when in rest, notwithstanding the absence of vibratory and bodily motions which are present when the vehicle is moving. These vibrations exert a very considerable disturbing influence upon the centrifugal action of the governor, and their effect is compensated in general by making the spring load heavy and the dash-pot sluggish, and by the symmetrical arrangement of the supplementary centrifugal elements, all of which collaborate to maintain the same character of governor control regardless of the vibrations.

The lower end of the control rod 14 is assumed to be connected or provided with a suitable handle or operating means, and the slot in its upper end, which engages the supplementary centrifugal elements, may be so fashioned as to permit it to operate the rod 12 and governor lever 1 irrespective of the governor balls, as will be evident.

I claim:

1. The combination with the governor, lever or member of a combustion engine, of a centrifugal governor comprising a set of centrifugal elements normally controlling such lever, another set of centrifugal elements adapted to supplement the said first set and means for bringing such supplementary set into operation while the governor is rotating.

2. The combination in a combustion engine, having a governor lever or member of a centrifugal governor having a centrifugal element adapted to act on such member to control the engine speed, a dash-pot retarding such action, a supplementary centrifugal element also adapted to act on such member and means for putting such supplementary element into and out of operation while the governor is rotating.

3. In a combustion engine, a governor controlling the same, having upwardly extending fly-ball-levers, a spring opposing the outward centrifugal movement thereof and a dash-pot controlled member through which such levers may affect the engine, in combination with means operative while the governor is rotating for rendering one or more of such levers ineffectual upon the engine.

4. A governor for combustion engines, comprising fly-ball levers, a thrust-collar upon which they may act, a dash-pot controlling the movement imparted by or through the collar and means engaging certain of the levers while in action to hold them inactive.

5. The combination with a combustion engine mounted on a vehicle for driving the same and having a centrifugal governor, of two sets of centrifugal elements adapted to

control the speed of the engine, a dash-pot controlling the movement produced by such elements, and means for putting one of said sets of elements into and out of operation while the engine is in operation.

In testimony whereof, I have signed this

specification in the presence of two witnesses.
